UNITED STATES PATENT OFFICE

2,285,720

DEVICE FOR RETAINING HEAT IN MOTOR OIL

Septer S. Joy, Terre Haute, Ind., assignor of twenty-four per cent to Charles A. Crawford, seventeen and one-half per cent to Michael John Grogan, ten per cent to George Oltean, twenty-five per cent to Mary Frances Craft, and five per cent to Max Menestrina, all of Terre Haute, Ind.

Application May 19, 1941, Serial No. 394,186

12 Claims. (Cl. 184—104)

The present invention relates to improvements in devices for retaining heat in motor oil and consists in certain improvements over the similar device disclosed in my prior Patent No. 2,228,460 granted January 14, 1941.

In common with the objects as stated in the prior patent aforesaid, the present invention aims to withdraw, from the crankcase or sump, the lubricating oil when the internal combustion engine or motor is to be discontinued in operation for such a period of time as would permit the oil to cool down below good lubricating temperature, and transfer such oil, then hot from engine operation, to an insulated container or receptacle where the oil is stored and its heat conserved and retained during the period of non-operation of the engine or motor, as when an automobile is garaged for the night, or when a motor car is left parked in the open in cold climates or temperatures.

It is essential to good engine operation and long life in the motor to have good lubrication at all times, and this is possible only when the lubricating oil is properly fluent and warm. This condition does not obtain for an initial period of time after starting a cold motor.

It is one of the objects of the invention to furnish the motor with a hot properly fluid oil at all times, and especially at the initial period referred to.

The present invention has for an object over the prior patent aforesaid an improved control arrangement in which the ignition of the motor is automatically disconnected when the crankcase or sump is devoid of sufficient lubricating oil for proper motor operation, whereby the operator cannot start the motor at the key switch; and wherein the motor ignition circuit is automatically restored to normal condition closable at the key switch when the oil has been evacuated from the heat-retaining reservoir and returned to the crankcase or sump.

Another object of the invention over those of the prior patent aforesaid is to provide an improved unified valve arrangement for admitting the oil from the crankcase or sump to the closed heat-insulated reservoir, at the same time evacuating air therefrom; and in providing for the free flow of oil from the reservoir, at the same time introducing vacuum-breaking air into the reservoir.

A still further object of the present invention over those of the prior patent aforesaid is to provide a temperature booster in the oil riser line from the crankcase or sump to the heat-retain-

ing reservoir for insuring a minimum temperature in the oil prior to its delivery to such reservoir.

With the foregoing and other objects in view, 5 the invention will be hereinafter more fully described and more particularly pointed out in the appended claims.

In the drawings in which like parts are denoted by similar reference characters throughout the several views.

Figure 1 is a fragmentary vertical section through an automobile showing the improved device applied thereto.

Figure 2 is a vertical section, on an enlarged 15 scale, through the improved reservoir.

Figure 3 is a diagrammatic view of the valve control showing all valves closed.

Figure 4 is a similar view showing the valves 20 positioned for drawing in oil to the reservoir from the crankcase or sump.

Figure 5 is also a similar diagrammatic view showing the position of the valves when the oil is being evacuated from the reservoir.

Figure 6 is a fragmentary side elevation, with 25 parts broken away, showing the open position of the mercury switch.

Figure 7 is a fragmentary side elevation showing the temperature booster.

Figure 8 is a front elevational view of a modified form of temperature booster.

Figure 9 is a sectional view taken along the line 9—9 in Figure 8.

Figure 10 is a sectional view taken along the line 10—10 in Figure 8 with the coil in slightly 35 raised position.

Figure 11 is a front elevational view with parts broken away and parts shown in section of a central ignition control switch.

Figure 12 is a horizontal sectional view taken 40 along the line 12—12 in Figure 11, and

Figure 13 is a vertical sectional view taken along the line 13—13 in Figure 11.

Referring more particularly to the drawings, 45 10 designates the control rod which extends to the instrument panel, as shown in Figure 1, for easy manipulation.

As shown in Figure 2 the rod 10 has fixed on its lower end a bevel pinion 11 disposed in mesh with a similar bevel pinion 12 fast on a cam shaft 13. On shaft 13 is fixed a drain valve cam 14. This cam, as illustrated to better advantage in Figures 3, 4, and 5, is crescent shaped or half round. Disposed above the drain valve cam 14 is the drain valve tappet 15 carried on the lower end of the drain valve stem 16. The oil drain

valve 17 is carried upon the upper end of stem 16 and is normally kept closed by coil spring 18 expanding downwardly against the collar 19 fixed on the valve stem 16.

The valve 17 controls the outflow of oil through the drain conduit 20. This conduit 20, as shown in Figure 1 connects with the filling neck 48 through which lubricating oil is introduced into the crankcase or sump 49 of the internal combustion engine or motor.

The dashboard of the vehicle carrying motor 50 is designated at 51 and the instrument panel at 52.

The reservoir for the oil is shown at 21 as being conveniently carried by the forward portion of the dash 51 at a suitable elevation to permit draining of the hot oil therefrom by gravity through the conduit 20 to the crankcase or sump 49 by way of filling neck 48. The reservoir 21 may be of the Dewar construction or of any other suitable construction in which double vacuum walls or other type of heat insulation is employed for the purpose of preventing dissipation of the heat from the oil stored in this closed container or receptacle 21.

Reverting to Figure 2, at 22 is represented an upwardly extended oil intake tube which receives oil from the crankcase or sump from an oil intake tube or supply line 23. As shown in Figure 1 the line 23 connects with a low point in the crankcase or sump 49. It will be noted that the tubes or conduits 22 and 23 are separate and independent from the drain conduit 20 and the drain valve 17.

As shown more particularly in Figures 3, 4 and 5 the lower end of tube 22 is shown as fitted in a plug 53 and the upper end of tube 23 is shown as fitted in a plate 54. At the upper end of tube 23 is a valve seat for the oil intake valve 25, this valve being biased to its seat by coil spring 55. The valve is carried by a stem 56 having a tappet 57 cooperating with cam 34 fixed on the shaft 13.

An air valve 24 controls the inflow and outflow of air to reservoir 21 and is under the control of a cam 26 fixed on shaft 13. This cam 26 is full round having an opening drilled off-center to open the air valve 24 with either the oil drain valve 17 or the oil intake valve 25. Air tube 33 extends upwardly in the reservoir 21 from plug 53 and parallels oil intake tube 22.

On these tubes 22 and 23 is slidably mounted float 27 restricted in its rising movement by the stops 28 on one or both of the tubes 22, 33. A mercury balance switch 29 is pivoted at 30 upon tube 22 or other support within reservoir 21. A weight 31 of sufficient mass overbalances the empty oil barrel 58, which is positioned to receive oil from the gooseneck 59 at the upper end of tube 22. In the lower portion of oil barrel 58 are a number of perforations 59 to allow the restricted escape of oil therefrom. A lever 60 and a connecting cable 61 serve as one means of connecting oil barrel 58 and weight 31.

Below the oil barrel is a second float 32 possessing sufficient buoyancy to lift the full oil barrel 58. The float 32 normally rests on stops 62 on either or both of the extension tubes 22 and 33.

The air extension tube 33 connects with a flexible vacuum tube 35 extending over to the intake manifold as shown in Figure 1.

A steel wire or other rod connection 36 is carried by the lower float 27 and extends loosely through an eye 37 on the mercury switch 29, the rod 36 having a head 63 larger than the open

eyelet guide 37. The switch contacts 64 and 65 connect with the leads 66 and 67 included in the ignition circuit of the motor.

The lower mouth of the reservoir 21 about the plug 53 is sealed by neoprene insulation 38 or other appropriate insulation. The plate 54 and plug 53 are removably held in the insulating collar 38 in any appropriate manner as by the flange 68 on the valve case 69 and the fastenings 70.

10 The air valve 24 is urged downwardly by spring 71 against its seat at the upper end of tube 35, the valve 24 being carried by a valve stem 72 having at its lower end a tappet 73 engaging the cam 26.

15 The lower end of the case 69 is provided with a removable bottom 39.

The bevel gears 11 and 12 are secured in a gear case 74 which may be attached by appropriate fastenings to the valve case 69.

20 At 40 is represented a metal case cover to protect the Dewar insulated reservoir. Sponge rubber shock insulators 41 stabilize sections of the reservoir 21 and may also stabilize and absorb shocks between the metal case and the inner wall construction of the reservoir.

25 Referring more particularly to Figure 7, the intake oil conduit 23 is shown as having included therein a number of turns or coils 42 adjacent the motor exhaust manifold 43. This coil 42 forms a temperature booster, the coil being held to the manifold by U-shaped brackets 47 of expansion or thermostatic metal having the function to move the oil tubes or coils 42 away from the exhaust manifold 43 when the metal of the manifold becomes sufficiently hot, so that the tubes or coils 42 are not heated in excess of requirement.

30 In operation, assuming that the motor has been running and that the car is to be garaged or parked, or in other words assume that the motor is to be stopped and not to be used for an extended period of time, say from one half hour to thirty six hours, and that the temperature estimated to be acquired by the oil during such period is lower than that decreed for proper lubrication.

35 Under such circumstances the warm oil is to be withdrawn from the crankcase. While the motor is still running at idle-speed, the hand control 10 on the instrument panel 52 is turned one quarter way round to the right, thus rotating bevel gears 11 and 12, and through the latter the shaft 13 and its three cams 14, 26 and 34. The position is that shown in Figure 4 where the valves 24 and 25 are both opened by their respective cams 26 and 34. The opening of valve 24

40 causes the interior of reservoir 21 to be placed in communication with the intake manifold which thus withdraws air from the reservoir 21 through the tubes 33 and 35. The vacuum thus produced in the reservoir 21 lifts the oil from the crankcase or sump 49 through tubes 23 and 22 into the reservoir 21.

45 The first oil to enter flows into the small oil barrel 58, which because of the weight of oil, remains in its lower position, holding the mercury switch 29 at "on." The oil overflows the oil barrel 58 and begins to fill the reservoir 21. After a certain level has been reached, for instance after one and a half pints of oil is received in the reservoir the lower float 27 rises up to stops 28, lifting rod 36 up through eyelet 37 and elevating head 63 above such eyelet. This position of the float 27 is shown in Figure 6, wherein the balanced switch 29 is relieved of the weight of the lower float 27.

50 In case there is insufficient oil in the crank-

case; say only two or three quarts, to fill the insulated reservoir 21, when the last of this insufficient quantity of oil is delivered to oil barrel 58, such oil will drain out of the small drain holes 59 at the base of the oil barrel 58. The loss of the oil-weight overbalances the oil barrel 58 causing weight 31 to descend in the path of the right arm of the mercury switch 29; thus tripping the mercury switch 29 to the "off" position shown in Figure 6 and causing the motor to stop.

When the motor stops, turn the hand control back to a position where the cams will be as shown in Figure 3 with all valves closed. The reservoir 21 is now sealed air-tight from cold air and the temperature of the oil will be retained.

When the motor is to be again operated, the hand control 10 is rotated, say a quarter turn to the left, or to such position as illustrated in Figure 5 with the drain valve 17 and the air valve 28 both open. The oil is thus allowed to drain through the tube 20 back to the crankcase while air enters the reservoir 21 by way of the tubes 35 and 33 from the intake manifold. Therefore the oil, while draining, will not become airlocked in the reservoir.

As the oil drains out the lower float 27 will descend, drawing the rod 36 through the eye 37, and finally when the head 63 engages the eye 37, pulling the mercury switch back to the "on" position shown in Figure 2. The operator can see the ignition circuit close by observing the ammeter dial. The indicator of the ammeter will be deflected over the dial in the discharge direction in a short while after the draining of the oil begins, as it only requires a very short while, say one minute, to drain one gallon of oil from the reservoir.

In the event that a greater quantity of oil than the three quarts mentioned enters the reservoir, the upper or full capacity float 32 will ride up, lifting the oil barrel 58 and allowing weight 31 to tilt mercury switch 29 to the "off" position.

Figure 3 shows the position of the cams with all valves closed. This is the position assumed when the reservoir 21 is full of oil or when the crankcase is full and the engine in use.

Figure 4 shows both oil and air valves open for the drawing of the oil into the reservoir 21 and the expulsion of air from the reservoir.

Figure 5 shows the position of the cams and valves when draining oil from the reservoir 21 where air is allowed to enter the reservoir above the receding level of the oil.

In actual construction there may be no metal to metal contact between the extended tubes 22 and 33 and the valve base as all inside parts are insulated with cork gaskets at the connection with the base. This eliminates loss of heat through conduction of cold from outside metal. The Dewar insulated reservoir is "set" and sealed in neoprene 38 which reduces shock from vibration of the motor.

Referring more particularly to Figure 7, the importance of a sufficiently hot oil at the time the oil is drawn into the reservoir is believed to be obvious. It seems equally obvious that the oil in the crankcase will not be as hot after the motor has been running only a short time as it will be when the motor has been running a longer time. For the purpose of insuring a minimum low temperature for the oil when drawn into the container, the temperature booster is used where the oil is required to pass through the coils 42 against or adjacent the exhaust man-

ifold 43. The oil is thus heated by heat acquired from the manifold. The rapidity with which the exhaust manifold 43 becomes heated is availed of in this construction. By this means the oil, if insufficiently hot, will be raised to the requisite temperature, say 150° F. before it enters the reservoir.

The word "crankcase" in the claims will be understood to cover those situations where a sump is employed instead of a crankcase.

Referring more particularly to Figures 8, 9, and 10, these figures show the temperature booster heat control in a modification of Figure 7 wherein 42^a indicates the temperature booster coil and 43^a represents the exhaust pipe or exhaust manifold. In this instance, the coils 42^a are carried by one or more coil brackets. Each bracket preferably consists of divided sections 80 and 81 having semi-cylindrical mating depressions to fit about the oil pipes 42^a. Bolts or other fastening means 82 secure, or clamp, the sections 80 and 81 upon the coil 42^a. A bracket arm 83 is integral, or connected in suspending relation, with the coil bracket, this lift arm being pivoted, as at 84, to the motor block 50 or other convenient support.

The lift arms 83 include horizontal portions normally resting upon thermostatic bars which are composed of an upper bar 85 of iron and a lower bar 86 of brass which has a different coefficient of expansion and will expand at a more rapid rate, when heated, than the iron. These two bars 85 and 86 form a thermostatic couple, being secured together by the rivets 87. The whole thermostatic bar is supporting at a central or intermediate portion by a stay bolt 88, leaving the two end portions free to curl up under the influence of heat from the exhaust pipe or exhaust manifold to greater or less extent dependent upon the value of such heating.

Figure 9 shows the normal position of the coil brackets at normal temperatures. Figure 10 shows that excessively high temperatures curl the ends of the thermostat upwardly, lifting therewith the lift arms 83, thus moving the coil 42^a outwardly and away from the exhaust pipe 43^a so as to prevent undue heating of the oil.

Referring more particularly to Figures 11, 12 and 13, these figures show the central ignition control switch. In the event of the device being installed on aircraft, the balanced ignition control located within the thermal reservoir would be disturbed on acrobatic maneuvers of the plane, such as when the plane is flying in any position other than horizontal, like a roll, loop, bank or dive, etc.

The central ignition control switch automatically cuts out the mercury at a time when the oil has been returned to the crankcase or sump and before the airplane motor is started, thus eliminating any disturbance in the ignition circuit at a time when the plane goes off-horizontal positions, or at any other time.

The central ignition control switch is not limited to aircraft but is adaptable to all internal combustion motors.

The small flexible wires 66 and 67, Figure 2, may not be heavy enough to carry the load when a motor is turning at a high rate of speed, and ordinarily would set up a resistance. Use of the central ignition control switch will eliminate that possibility.

In Figures 11, 12 and 13 the central rod is shown at 10^a and controls the operation of the oil device and the central switch. The shaft 10^a

has affixed thereto, as by a pin 90, a clutch disk 91 which cooperates with the rotor 92 of the switch. Ratchet teeth 93 and ratchet sockets 94 are provided between these two members 91 and 92 in such relation that when the member 91 is rotated by shaft 10^a in a clockwise or right hand direction it will pick up member 92 and rotate the same; but on reverse rotation of shaft 10^a and member 91, that is in a counterclockwise or left hand direction, the inclined walls of the recesses 94 will slide over the inclined walls of the teeth 93. In order to do this, the disk 92 must be capable of moving away from the member 91. To this end, and for the purpose of keeping the two members 92 and 91 and the teeth and sockets up to one another and engaged, I mount the disk 92 loosely on the shaft 10^a so that it may freely rotate around said shaft and also slide axially on the shaft toward and from the disk 91. A backing plate 95 under the pressure of a spring 96 urges disk 92 axially toward disk 91; the backing plate 95 being prevented from rotating by the headed pins 97 which are carried by an adjacent support. Ratchet teeth 98 on the backing plate 95 engage ratchet sockets in the disk 92. The abrupt and inclined shoulders of these ratchet teeth and sockets 98 and 99 are in reverse relation with respect of the teeth and sockets 93 and 94. This arrangement permits disk 92 to be rotated in a clockwise direction and only in a clockwise direction and avoids retrograde rotation of the switch disk 92.

The disk 92 carries a bridge piece 100 terminating in terminals 101 which project at diametrically opposite points on the circular disk 92, as shown in Figure 13, in order to brush against the fixed or stationary contacts 102 and 103 supported in the casing 104.

The wire 66 from the mercury switch 29 of Figure 2 is grounded on the casing 104 as shown at 105 as is also a lead 106 to the coil wire 107 which connects directly with the fixed electrode 102. The wire 67 of the mercury switch 29 connects with the other fixed electrode 103. At 108 is shown a lead from the electrode 103 to the distributor. The bridge 100 forms a direct connection between the coil and the distributor when the motor is in normal operation. The backing plate 95 acts as a lock for the switch disk 92 preventing that disk from being turned to the left. Moreover, the backing plate 95 in the right hand rotation of the disk 92, by reason of the ratchet teeth and sockets 99 causes disk 92 to tend to shift to the right thus holding the teeth 93 in the sockets 94 and insuring a good drive connection between disks 92 and 91. The backing plate 95 is constantly sliding axially of shaft 10^a and the pins 97 during this movement as the inclined walls of the sockets and teeth 99 and 98 ride over one another in the right hand rotation of the disk 92. The spring pressure of the coil spring 96 quickens the action of the switch. A number of capped screws 109 may be used to fasten the switch case to the base.

The ignition circuit is routed through the leads 67 to the distributor when the bridge piece 100 assumes the dotted line position shown in Figure 13; that is when the contacts 101 are turned through an angle of substantially 90° from the full line position of Figure 13. This occurs when the withdrawal or drain operation is in progress.

It will be apparent from Figure 13 that the central switch cuts out the mercury switch thereby eliminating any disturbance of the ignition

circuit when the airship or airplane is doing acrobatic maneuvers and is off horizontal. In case the small flexible wires 66 and 67 of the mercury switch are not heavy enough to carry the load where the motor is running at high speed (particularly truck motors) which would ordinarily set up a resistance, the central ignition (or "direct to motor") switch eliminates this. In other words, this new switch strengthens the device for use on all motors.

The part 15, Figures 2 and 6, is an arm connection extended from switch 29. The weight 31 connects with the part 15 by the means of a hinge connection at the base of weight 31. The switch 29 is a mercury or other fluid type of switch enclosed in a glass tube and it is very important that the weight 31 should not hit against the switch 29 and break the glass tube; however the glass tube will ordinarily be protected by a substantial incasement of Bakelite or other suitable material.

It is obvious that various changes and modifications may be made in the details of construction and design of the above specifically described embodiment of this invention without departing from the spirit thereof, such changes and modifications being restricted only by the scope of the following claims:

What is claimed is:

1. In combination with a crankcase of a motor containing a body of lubricating oil, of a device for retaining the heat in the motor oil during periods of non-operation of the motor comprising a closed and heat-insulated reservoir, a removable member insertable in the lower portion of the reservoir, an oil inlet valve in said member in communication with the interior of the reservoir and with said crankcase, an oil drain valve in said member in communication with the interior of the reservoir and with said crankcase, an air valve in said member in communication with the interior of the reservoir and with a source of air and vacuum supply, means biasing said valves to closed position, and means for selectively opening said valves.
2. In combination with a crankcase of a motor containing a body of lubricating oil, of a device for retaining the heat in the motor oil during periods of non-operation of the motor comprising a closed and heat-insulated reservoir, a removable member insertable in the lower portion of the reservoir, an oil inlet valve in said member in communication with the interior of the reservoir and with said crankcase, an oil drain valve in said member in communication with the interior of the reservoir and with said crankcase, an air valve in said member in communication with the interior of the reservoir and with a source of air and vacuum supply, means biasing said valves to closed position, means for selectively opening either the oil intake or the oil drain valve, and means grouped for simultaneous actuation with last named means for opening said air valve when either said oil intake or said oil drain valve is opened.
3. In combination with a crankcase of a motor containing a body of lubricating oil, of a device for retaining the heat in the motor oil during periods of non-operation of the motor comprising a closed and heat-insulated reservoir, a removable member insertable in the lower portion of the reservoir, an oil inlet valve in said member in communication with the interior of the reservoir and with said crankcase, an oil drain valve in said member in communication with the interior of the reservoir and with said crankcase, and means grouped for simultaneous actuation with last named means for opening said air valve when either said oil intake or

- 70
- 75

of the reservoir and with said crankcase, an air valve in said member in communication with the interior of the reservoir and with a source of air and vacuum supply, means biasing said valves to closed position, tappets connected to said valves, cams for engaging said tappets to open the valves, said cams being so constructed and arranged as to open the oil intake and oil drain valves only alternately and to open said air valve simultaneously with the opening of either of said oil valves, and a common operating and control means for said cams.

4. In combination with a crankcase of a motor containing a body of lubricating oil, of a device for retaining the heat in the motor oil during periods of non-operation of the motor comprising a closed and heat-insulated reservoir, a removable member insertable in the lower portion of the reservoir, an oil inlet valve in said member in communication with the interior of the reservoir and with said crankcase, an oil drain valve in said member in communication with the interior of the reservoir and with said crankcase, an air valve in said member in communication with the interior of the reservoir and with a source of air and vacuum supply, means biasing said valves to closed position, tappets connected to said valves, cams cooperating with said tappets to open the valves, said cams so constructed and arranged as to open the air valve along with the opening of either the oil intake or the oil drain valves but to open the two latter valves only alternately, a common shaft on which said cams are fixedly mounted, and a single control member for rotating said shaft to alter the angular positions of the cams with respect to the respective tappets.

5. In combination with a crankcase of a motor containing a body of lubricating oil, of a device for retaining the heat in the motor oil during periods of non-operation of the motor comprising a heat-insulated reservoir, an oil intake conduit communicating at a low point with said crankcase and with said reservoir, an oil intake valve controlling the movement of oil through said intake conduit into the reservoir, a drain conduit from said reservoir to the crankcase, a drain valve controlling the outflow through said drain conduit, an air conduit communicating with said reservoir and with the intake manifold of the motor, an air valve for controlling the movement of air in either direction through said air conduit, means yieldably biasing all of said valves independently to closed position, and means grouped for simultaneous actuation close to said valves for opening the valves in grouped arrangement in which the air valve is opened when either of the other valves is opened but the oil intake and oil drain valves are opened only alternately.

6. In combination with a crankcase of a motor containing a body of lubricating oil, and an ignition circuit for the motor, of a device for retaining the heat in the motor oil during periods of non-operation of the motor comprising a closed heat-insulated reservoir, means for causing the oil to be drawn into said reservoir from the crankcase, means for controlling the return of the oil from the reservoir to the crankcase, a normally closed switch in the ignition circuit, means actuated only when a pre-determined volume of oil is received in said reservoir for moving said switch to open position to interrupt the ignition circuit, and other means actuated when the reservoir receives a lesser volume of oil for

also moving said switch to open position to interrupt the ignition circuit.

7. In combination with a crankcase of a motor-containing a body of lubricating oil, and an ignition circuit for the motor, of a device for retaining the heat in the motor oil during periods of non-operation of the motor comprising a closed heat-insulated reservoir, means for causing the movement of the oil from the crankcase into said reservoir, means for evacuating the reservoir and returning the oil to said crankcase, a movable switch in the ignition circuit, means for closing said switch when oil is substantially evacuated from said reservoir, and means independent of said last named means for opening the switch when the reservoir is partly or wholly filled with oil.

8. In combination with a crankcase of a motor containing a body of lubricating oil, and an ignition circuit for the motor, of a device for retaining the heat in the motor oil during periods of non-operation of the motor comprising a closed heat-insulated reservoir, means for causing oil from the crankcase to be drawn under control into said reservoir, means for causing under control the evacuation of oil from the reservoir to the crankcase, a switch in the ignition circuit, float means having connection to said switch to cause closing thereof when oil is substantially evacuated from the reservoir, said last named means having a loose connection with said switch to release the switch when the float is in the raised position, and means for causing the opening of the switch when oil is received in the reservoir.

9. In combination with a crankcase of a motor containing a body of lubricating oil, and an ignition circuit for the motor, of a device for retaining the heat in the motor oil during periods of non-operation of the motor comprising a closed heat-insulated reservoir, means for causing oil from the crankcase to be drawn under control into said reservoir, means for causing under control the evacuation of oil from the reservoir to the crankcase a switch in the ignition circuit, float means having connection to said switch to cause closing thereof when oil is substantially evacuated from the reservoir, said last named means having a loose connection with said switch to release the switch when the float is in the raised position, a weight movably mounted and positioned to open said switch, and oil receptacle in balanced relation to said weight means having capacity to overbalance the weight means when full, said oil container movably mounted and having restricted discharge for oil therefrom.

10. In combination with a crankcase of a motor containing a body of lubricating oil, and an ignition circuit for the motor, of a device for retaining the heat in the motor oil during periods of non-operation of the motor comprising a closed heat-insulated reservoir, means for causing oil from the crankcase to be drawn under control into said reservoir, means for causing under control the evacuation of oil from the reservoir to the crankcase, a switch in the ignition circuit, float means having connection to said switch to cause closing thereof when oil is substantially evacuated from the reservoir, said last named means having a loose connection with said switch to release the switch when the float is in the raised position, and weight means inferior in weight to said float means for opening the switch when said float means is raised.

11. In combination with a crankcase of a motor containing a body of lubricating oil, and an ignition circuit for the motor, of a device for retaining the heat in the motor oil during periods of non-operation of the motor comprising a closed heat-insulated reservoir, means for causing oil from the crankcase to be drawn under control into said reservoir, means for causing under control the evacuation of oil from the reservoir to the crankcase, a switch in the ignition circuit, float means having connection to said switch to cause closing thereof when oil is substantially evacuated from the reservoir, said last named means having a loose connection with said switch to release the switch when the float is in the raised position, weight means for opening said switch, an oil container movably mounted and connected to said weight and overbalanced by the weight when empty, said oil container having restricted discharge therefrom, and a float positioned beneath and acting to lift said oil container.
12. In combination with a crankcase of a motor containing a body of lubricating oil, and an ignition circuit for the motor, of a device for retaining the heat in the motor oil during periods of non-operation of the motor comprising a closed heat-insulated reservoir, means for introducing oil from the crankcase to the reservoir under control including a riser tube in the reservoir having a gooseneck discharge at its upper portion, means for evacuating the oil from the reservoir back to the crankcase, means for introducing air or vacuum under control to the reservoir including a riser tube having its upper open end adjacent the upper part of the reservoir, upper and lower floats slideable on said riser tubes, stop means for arresting the upward movement of the lower float, rest means for supporting the upper float, a pivoted switch in the ignition circuit, an eye carried by the switch, a headed rod on the lower float, said rod extending through said eye, a weight positioned to open said switch, a lever connected flexibly to said weight, an oil barrel positioned movably beneath said gooseneck and above the upper float and connected to the other end of said lever, said oil barrel having oil discharge openings in its lower portion.
